(57) **CLAIM**

The ornamental design for a brewing system, as shown and described.

DESCRIPTION

FIG. 1 is a top, front perspective view of a brewing system illustrating our new design in a first configuration;
FIG. 2 is a top, rear perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan view thereof;
FIG. 9 is a top, front perspective view of the brewing system with upper lids in an open configuration;
FIG. 10 is a top, rear perspective view thereof;
FIG. 11 is a top, front perspective view of the brewing system with a user interface in an open configuration;
FIG. 12 is a top, front perspective view of the brewing system with a front door in a closed configuration; and,
FIG. 13 is a top, rear perspective view of the brewing system with a rear door in a closed configuration.
The broken lines in the drawings illustrate portions of the brewing system that form no part of the claimed design.

1 Claim, 12 Drawing Sheets
